SLITTING APPARATUS

Charles W. Leguillon, Akron, Ohio, assignor to
The B. F. Goodrich Company, New York, N. Y.,
a corporation of New York

Application July 5, 1934, Serial No. 733,737

5 Claims. (Cl. 164—60)

This invention relates to slitting apparatus and is especially useful where it is necessary to slit very thin material such as unvulcanized sheet rubber to produce very narrow strips of thread-like dimensions.

It has heretofore been proposed to slit a sheet of material into narrow ribbons by the cooperation of two sets of discs mounted upon parallel shafts with the discs operating in intercalated relation to shear the material. This has heretofore been determined to be difficult in commercial practice because of the difficulties encountered in keeping the discs sharpened and in operative engagement.

Where elastic materials such as unvulcanized or vulcanized rubber or plastic materials are to be operated upon, the plasticity and elasticity of the material interferes with the cutting operation and requires close adjustment of the discs.

The principal objects of the present invention are to provide resilient lateral support of the cutting discs, to provide automatic adjustment of the discs, to provide collective and local adjustment thereof, and to accomplish the slitting into narrower strips than has heretofore been possible.

Other objects are simplicity of construction and ease of adjustment.

Further objects will appear from the following description and the accompanying drawing.

Of the drawing:

Fig. 1 is a front elevation of the preferred form of the device.

Fig. 2 is a sectional detail view, taken on line 2—2 of Fig. 1.

Fig. 3 is a sectional detail view, taken on line 3—3 of Fig. 1.

Fig. 4 is an enlarged sectional view of the cutting discs and their separators taken on line 4—4 of Fig. 2.

Referring to the drawing, the numerals 10 and 11 designate respectively the upper and lower parallel shafts upon which the cutting discs are mounted. These shafts are rotatively mounted in bearings supported by frame members 12, 13. Frames 12 and 13 are rigidly mounted upon a bed plate 14 and are formed with vertical slots in which boxes 15, 16 for rotatably supporting the shaft 11, and boxes 17, 18 for rotatably supporting the shaft 10 are slidably mounted. Boxes 15, 16 rest at the bottom of the slots while boxes 17 are supported thereabove by suitable blocking.

Cap members 19 and 20 are fixed to the frames 12, 13 across the open ends of the slots, being held in

place to bolts 21, 22. Screws 23, 24, passing through threaded openings in the caps, hold the boxes 17, 18 in place.

A pair of gears 25, 26 are fixed to the projecting ends of shafts 10 and 11 and are engaged with each other to cause the shafts to turn in unison. Another gear wheel 27 is also fixed to shaft 11 and engages a pinion (not shown) whereby the device is driven.

Shaft 10 is formed with a shoulder 28 near the frame member 12 and a cylindrical portion 29 having a keyway in which a key 30 is fixed.

The cutting discs 31, which are slidably mounted on the keyed portion of the shaft, have cylindrical faces, and their sides are slightly dished to relieve their cutting edges. Resilient spacing rings 33, preferably molded from rubber or similarly resilient material, such as that described in U. S. Letters Patent No. 1,929,453, are slidably mounted on the shaft between the cutting discs. The cutting discs and spacing rings, alternately arranged, are prevented from turning on the shaft by the key 30 and are retained on the shaft between slidable collars 34 and 35.

In order to provide for automatic adjustment of the discs and collective adjustment of their spacing, a collar 36 is slidably mounted on the shaft and is provided with means for holding it laterally against the collar 34. For this purpose a convenient arrangement is a plurality of screws 37 axially disposed parallel to shaft 10 and entering equally spaced threaded apertures in collar 36. These bolts act as a series of circumferentially spaced screw jacks. The shaft 10 is threaded to engage an adjusting collar 38 and a lock collar 39, whereby pressure may be applied along the shaft to the collar 36. A resilient ring of rubber or similarly resilient material 40 and a metal washer 41 are located between collars 36 and 38, the purpose of the resilient washer being resiliently to compensate for any slight variations of adjustment.

In order to reduce the pressure necessary to accomplish adjustment of the longitudinal spacing of the cutter discs and to more resiliently support the discs laterally, the spacing rings 33 are preferably formed with flow cavities 33a provided by forming the rings with concentric raised beads 33b or other projections.

The shaft 11 is similarly provided with similar cutting discs 42 spaced apart by resilient rings 43. The cutting discs and spacing rings are held between rigid collars 44 and 45, the collar 44 abut-

ting a shoulder 46 of the shaft and the collar 45 being held between the cutting discs and a threaded adjustment collar 47 engaging screw threads formed on the shaft.

5 As compensation for slight variations of adjustment and of thickness of the discs has been provided for on shaft 10, the collar 36 of shaft 10 is not essential to shaft 11 and is replaced by a plain collar 48. Resilient washers 49 and 50 are, however, provided to take care of slight deflections of the cutting discs. A locking collar 51 is provided as on shaft 10.

10 The cutting discs 31 and 42 are arranged to cooperate in intercalated shearing relation as seen in Figs. 1 and 2. As the adjustment has been shown applied to one end only of the rolls, it is necessary that one of the shafts, preferably shaft 11, have free endwise movement so that it may float axially in making the adjustments.

15 While the device may be used with relatively wide-faced cutters, the principal advantage of the invention is that it may be used for slitting extremely narrow strips. For instance when the device is used to slit a very thin sheet of unvulcanized rubber deposited from a natural or artificial aqueous dispersion of rubber, it is possible to use cutting discs having a face fifteen thousandths of an inch or less wide and correspondingly thin spacing rings and successfully to cut such material into ribbons not over fifteen thousandths of an inch wide, at least a hundred of such ribbons being cut simultaneously.

20 As cutting of materials such as sheet rubber is facilitated by lubrication of the sheet, it is advisable to form the resilient spacing rings of material which will be substantially unaffected by the lubricant used. Where the lubricant is water, soft vulcanized rubber may be used, but where oily lubricants are used the spacing rings should be made of a material having a high resistance to such substances, such as the material described in U. S. Letters Patent No. 1,929,453.

25 In the operation of the device, the screws 37 are first adjusted so that each projects from the collar 36 by the same amount. Cutters and spacing washers of the proper width are assembled on the shafts, and, by adjustment of collars 38 and 47, the proper spacing of the cutting discs is accomplished with the cutting discs of the respective shafts in intercalated relation. The shafts are then rotated and a sheet of the material to be cut is fed between the cutters. Should it be found that the cutting discs fail to cut at some lateral zone of the sheet, the screw 37 in line with that zone is adjusted so as to advance it toward the cutting discs until successful cutting occurs.

30 After the machine has operated for such a time that the cutters become dull, the shafts may be removed with the cutters thereon and the cutters ground across the faces thereof simultaneously without removing them from the shafts.

I claim:

1. Apparatus for slitting sheet material, said apparatus comprising a pair of parallel driven shafts, a plurality of cutting discs slidably but non-rotatably mounted upon each shaft with the discs of one shaft engaging those of the other in intercalated relation, lubricant resistant resilient spacers between successive discs of at least one of the shafts, said spacers having chambered lateral faces to facilitate reduction in thickness of the spacers by pressure applied axially of the shaft, and means carried by the shaft for simultaneously adjusting the spacing of the discs by axial compression of the spacers. 5

15 2. Apparatus for slitting sheet material, said apparatus comprising a pair of parallel driven shafts, a plurality of cutting discs slidably but non-rotatably mounted upon each shaft with the discs of one shaft engaging those of the other in intercalated relation, lubricant resistant resilient 20 spacing means mounted on each shaft between the cutting discs thereon, said spacing means comprising rings having their lateral faces ribbed to provide flow cavities and means on each shaft for simultaneously adjusting the spacing of all 25 the cutting discs thereon by axial compression of the spacing discs.

3. Apparatus for slitting sheet material, said apparatus comprising a pair of parallel driven shafts, a plurality of cutting discs slidably but 30 non-rotatably mounted on each shaft with the discs of one shaft engaging those of the other in intercalated relation, resilient spacing means mounted on each shaft between the cutting discs 35 thereon, and means for simultaneously adjusting the spacing of the discs on one of the shafts locally of their peripheries to compensate for errors.

4. Apparatus for slitting sheet material, said apparatus comprising a pair of parallel driven shafts, a plurality of cutting discs slidably but 40 non-rotatably mounted upon each shaft with the discs of one shaft engaging those of the other in intercalated relation, resilient spacing means mounted upon each shaft between the cutting discs 45 thereon, means on each shaft for simultaneously adjusting the spacing of the discs thereon, and means on one of the shafts for simultaneously adjusting the spacing of the discs locally of their peripheries to compensate for errors.

5. Apparatus for slitting sheet material, said 50 apparatus comprising a driven shaft, a series of cutting discs slidably but non-rotatably mounted on said shaft, a cutting member adapted to cooperate with all of the discs on said shaft, resilient spacing members on said shaft between the cutting discs, means for simultaneously compressing all of the spacing members to change the spacing of the discs, and auxiliary means for varying the adjustment of the discs locally of their peripheries. 55
